UMBRELLA CARRYING GARMENT

Akivah Drasnin, Buffalo, N. Y.

Application May 18, 1948, Serial No. 27,738

5 Claims. (Cl. 2—247)

1

This invention relates to wearing apparel and more particularly to an umbrella carrying garment.

The principal object of the invention is to provide an outer garment such as a raincoat or the like in which a collapsed or folded umbrella can be carried while the garment is being worn and thus leave the hands and arms of the wearer free.

Another object is to provide such a garment in which the umbrella is concealed to render the umbrella inconspicuous from the exterior of the garment.

Another object is to provide such an umbrella carrying garment which is comfortable to wear either in an upright or sitting position, the umbrella being so arranged in the garment as not to interfere with the movement of the arms and legs of the wearer.

Another object is to provide such a garment in which the umbrella is readily accessible either from the outside or inside of the garment.

Another object is to provide such an umbrella carrying garment which protects the wearer from direct contact with the cloth of the umbrella so that if the umbrella when wet is arranged on the garment the wearer's inner garment will not absorb water from the umbrella.

A further object is to provide such an umbrella carrying garment which is simple in construction and inexpensive to manufacture.

Other objects and advantages of the invention will be apparent from the following description and drawings wherein:

Fig. 1 illustrates the drape of a garment embodying one form of the invention when the garment is worn by a person in an upright position and showing by broken lines the arrangement of an umbrella carried by the garment.

Fig. 2 is similar to Fig. 1 but showing the position of the umbrella when the wearer of the garment is seated.

Fig. 3 is a fragmentary substantially vertical central section on an enlarged scale through the umbrella carrying means shown in Fig. 1, the handle of the umbrella being shown as arranged within the outer pocket of the garment.

Fig. 4 is a fragmentary side elevation of the exterior of the upper portion of the garment shown in Fig. 3, this view looking at the left of Fig. 3 and showing the upper central portion of the outer pocket being broken away.

Fig. 5 is a view similar to Fig. 3 but showing the umbrella handle being arranged on the inside of the garment.

Fig. 6 is a fragmentary side elevation of the

2

interior of the garment shown in Fig. 5, this view looking at the right of Fig. 5.

Fig. 7 is a fragmentary horizontal section thereof taken on line 7—7, Fig. 3.

5 Figs. 8 and 9 are views similar to Figs. 1 and 2 and showing a garment embodying a modified form of the invention.

10 Fig. 10 is a fragmentary substantially vertical central section on an enlarged scale through the umbrella carrying means shown in Fig. 8.

Fig. 11 is a fragmentary side elevation of the interior of the garment shown in Fig. 10, this view looking at the right of Fig. 10.

15 Fig. 12 is a fragmentary substantially horizontal section thereof taken on line 12—12, Fig. 11.

20 A garment embodying one form of the invention is shown in Figs. 1—7. The garment there shown is intended to be illustrative of a full length raincoat having a hem line adjacent the knees of the wearer of the garment. This garment is shown as including a side panel 20 having an outer fabric 21 and an inner fabric or lining 22.

25 Means are provided for carrying a collapsed or folded umbrella in a comfortable and inconspicuous manner on the garment. For this purpose a sheath or pocket 23 is shown as being arranged on the lower part of the side panel 20 between the inner and outer fabrics 22 and 21 respectively thereof. This sheath 23 is shown as being located on the side of the garment toward the front thereof and arranged substantially vertically so that when the garment is worn the upper end of the sheath is adjacent the hip of the wearer, and the lower end of the sheath is adjacent the knee of the wearer.

30 Adjacent the upper end of the sheath 23, the side panel 20 is provided with an opening 24 through which an umbrella 25 can be inserted into or removed from the sheath 23 from either the outside or inside of the side panel 20. For this purpose, the inner and outer fabrics 22 and 21 are shown as being provided with substantially horizontal and registering slits, the inner and outer fabrics being preferably sewed together above the slits as indicated at 26 but below these slits these fabrics are not connected together.

35 The sheath 23 is shown as comprising inner and outer panels 28 and 29 respectively made of fabric material, preferably waterproof in character, and sewed together adjacent their side and bottom margins by a line of stitching 30 thereby forming a pocket 31 adapted to receive the umbrella 25. This line of stitching 30 also secures the sheath 23 to the inner fabric 22 of the side panel 20. To

support the sheath 23 additionally an outer line of stitching 32 is shown as connecting the sides and bottom of the inner panel 26 to the inner fabric 22. The upper edge of the outer panel 29 of the sheath is preferably sewed to the outer fabric 21 as indicated at 33 and the upper edge of the inner panel 28 is preferably sewed to the inner fabric 22 as indicated at 34. It will thus be seen that the mouth of the sheath 23 is adjacent the opening 24 and the umbrella 25 can be inserted into and removed from this sheath either from the outside of the side panel 20 as shown in Figs. 3 and 4 or from the inside of this side panel as shown in Figs. 5 and 6.

To cover the opening 24 and also to render the handle of the umbrella 25 inconspicuous when the umbrella is carried as shown in Figs. 3 and 4, an outer pocket panel 35 is shown as being sewed along its sides and bottom to the side panel 20. This pocket is in the usual location of side pockets for garments of the type in question and this pocket may be utilized to carry whatever the wearer desires. A flap or lapel (not shown) may be provided for the outer pocket if desired.

It will thus be seen that to insert the umbrella 25 from the outside of the garment the point of the umbrella is inserted between the side pocket panel 35 and the opposing portion of the outer fabric 21 into the opening 24 and into the mouth or inlet of the sheath 23, the umbrella being preferably of such length that when inserted the full length of the pocket 31 of the sheath the handle of the umbrella will traverse the opening 24 so as to retain the handle on the outside of the garment as shown in Figs. 3 and 4. To remove the umbrella it is merely necessary to lift the umbrella out of the sheath. It will be noted that the garment does not have to be opened at its front to insert or remove the umbrella from the outside of the garment. If desired the umbrella can be inserted and removed from the inside of the garment as shown in Figs. 5 and 6, this of course involving opening the front of the garment.

It will be understood that since the side panel 20 and sheath 23 are made of flexible material, the garment will drape or adjust itself to accommodate the umbrella when the umbrella handle is either on the outside or inside of the side panel 20 above the opening 24 therein.

It is preferred to arrange the sheath so that its axis is slightly inclined as shown in Fig. 1. The axis of the sheath 23 is shown as inclining downwardly and slightly forwardly of the side panel 20 of the garment so that when the umbrella 25 is carried in the sheath the umbrella rests comfortably against the thigh of the wearer and moves with the movements of the wearer's leg. Such disposition of the sheath 23 also prevents the umbrella 25 from catching under the leg when the person sits down. It will be seen that the sheath is so arranged that the opening 24 in the side panel 20 is adjacent the hip of the wearer so that when the person is walking or sits the umbrella pivots at the hip of the person.

It is also preferred to employ with the garment embodying the present invention an umbrella having an overall length generally conforming to the distance between the hip and knee joints of the size of person wearing the garment. Conventional umbrellas in such suitable sizes are available.

A garment embodying a modified form of the invention is shown in Figs. 8-12. The garment there shown is illustrative of a raincape particu-

larly suited for children and includes a side panel 40 made preferably of a rubberized sheet material which is waterproof. The side panel 40 is shown as being provided with an opening 41 through which the hand of the garment wearer can be inserted, this opening 41 being shown as a slit located at the side of the side panel 40 adjacent the hip of the wearer. A sheath 42 is shown as being arranged on the inside of the side panel 40 and below and slightly forward of the opening 41. The sheath 42 is shown as being formed by securing the sides and bottom edges of an elongated strip of flexible material 43 preferably waterproof in character, to the side panel 40 as by a line of stitching 44.

It will be seen that the mouth or inlet of the sheath 42 is adjacent the opening 41 so that by spreading this opening an umbrella 45 can be inserted through this opening and into the sheath 42 from the outside of the garment. Also, the umbrella 45 can be withdrawn from the sheath 42 through the opening 41. If desired the umbrella 45 can be inserted into and removed from the sheath 42 from the inside of the garment.

The axis of the sheath 42 is preferably inclined downwardly and slightly forwardly so as to possess the advantages described in connection with the form of the invention shown in Figs. 8-12.

In both forms of the invention the size of the umbrella receiving pockets of the sheaths 23 and 42 are such as to snugly hold the umbrella therein and prevent its unintentional or accidental displacement but yet permit the umbrella to be easily withdrawn.

From the foregoing it will be seen that the present invention provides an attractive garment for carrying an umbrella in a comfortable and inconspicuous manner when the umbrella is not being used. The umbrella can be inserted into or withdrawn from its sheath either from the inside or outside of the garment. Further, the invention is simple and can be inexpensively embodied in a garment as part of its original manufacture or incorporated into an existing garment by a simple modification thereof. The umbrella carrying sheath can be permanently or detachably secured to garment.

I claim:

1. In an outdoor umbrella carrying garment supported principally from the shoulders of the wearer, the combination comprising a side panel descending to at least the wearer's knees and covering the lateral outer side of the wearer's thigh, and fabric means secured to said garment and forming a vertically elongated sheath-like pocket open at its upper end and closed at its lower end and of a length approximately equal to the distance between the thigh and knee of the wearer and arranged in such position on the inner side of said side panel that said open upper end is generally in line with the hips of the wearer and said pocket extends downwardly along the lateral outer side of the wearer's thigh and with said lower end being arranged adjacent the wearer's knee in the erect position of the wearer, said open upper end of said pocket providing an inlet and outlet therefor for a collapsed umbrella of a length substantially equal to the length of said pocket thereby to permit said umbrella to be carried in said pocket with the upper end of said umbrella not extending above the wearer's hip whereby the wearer can walk, sit and bend freely without unsightly bulging from or interference with said umbrella in said pocket.

2. In an outdoor umbrella carrying garment

supported principally from the shoulders of the wearer, the combination comprising a side panel descending to at least the wearer's knees and covering the lateral outer side of the wearer's thigh, said side panel having an opening therethrough located generally in line with the hips of the wearer when in an erect position, and fabric means secured to said garment and forming a vertically elongated sheath-like pocket closed at its lower end and of a length approximately equal to the distance between the thigh and knee of the wearer and arranged in such position on the inner side of said side panel that the upper end of said pocket is adjacent said opening and said pocket extends downwardly along the lateral outer side of the wearer's thigh and with said lower end being arranged adjacent the wearer's knee in the erect position of the wearer, said opening permitting the passage of a collapsed umbrella of a length substantially equal to the length of said pocket into and out of said upper end of said pocket thereby to permit said umbrella to be carried in said pocket with the upper end of said umbrella not extending above the wearer's hip whereby the wearer can walk, sit and bend freely without unsightly bulging from or interference with said umbrella in said pocket.

3. In an outdoor umbrella carrying garment supported principally from the shoulders of the wearer, the combination comprising a side panel descending to at least the wearer's knees and covering the lateral outer side of the wearer's thigh and having outer and inner fabric elements, at least one of said fabric elements having an opening therethrough located generally in line with the hips of the wearer when in an erect position, and fabric means secured to said garment and forming a vertically elongated sheath-like pocket closed at its lower end and of a length approximately equal to the distance between the thigh and knee of the wearer and arranged between said fabric elements in such position that the upper end of said pocket is adjacent said opening and said pocket extends downwardly along the lateral outer side of the wearer's thigh and with said lower end being arranged adjacent the wearer's knee in the erect position of the wearer, said opening permitting the passage of a collapsed umbrella of a length substantially equal to the length of said pocket into and out of said upper end of said pocket thereby to permit said umbrella to be carried in said pocket with the upper end of said umbrella not extending above the wearer's hip whereby the wearer can walk, sit and bend freely without unsightly bulging from or interference with said umbrella in said pocket.

4. In an outdoor umbrella carrying garment supported principally from the shoulders of the wearer, the combination comprising a side panel descending to at least the wearer's knees and covering the lateral outer side of the wearer's thigh, a fabric member connected to said side panel so as to form on the side of said side panel a hand pocket having inner and outer walls, said inner wall having an opening therethrough located generally in line with the hips of the wearer when in an erect position and being nor-

mally covered by said outer wall, and fabric means secured to said garment and forming a vertically elongated sheath-like pocket closed at its lower end and of a length approximately equal to the distance between the thigh and knee of the wearer and arranged in such position on the inner side of said side panel that the upper end of said sheath-like pocket is adjacent said opening and said sheath-like pocket extends downwardly along the lateral outer side of the wearer's thigh and with said lower end being arranged adjacent the wearer's knee in the erect position of the wearer, said opening permitting the passage of a collapsed umbrella of a length substantially equal to the length of said sheath-like pocket into and out of said upper end of said sheath-like pocket thereby to permit said umbrella to be carried in said sheath-like pocket with the upper end of said umbrella not extending above the wearer's thigh whereby the wearer can walk, sit and bend freely without unsightly bulging from or interference with said umbrella in said sheath-like pocket.

5. In an outdoor umbrella carrying garment supported principally from the shoulders of the wearer, the combination comprising a side panel descending to at least the wearer's knees and covering the lateral outer side of the wearer's thigh, and fabric means secured to said garment and forming a vertically elongated sheath-like pocket open at its upper end and closed at its lower end and of a length approximately equal to the distance between the thigh and knee of the wearer and arranged in such position on the inner side of said side panel that said open upper end is generally in line with the hips of the wearer and said pocket extends downwardly and slightly forwardly along the lateral outer side of the wearer's thigh and with said lower end being arranged adjacent the wearer's knee in the erect position of the wearer, said open upper end of said pocket providing an inlet and outlet therefor for a collapsed umbrella of a length substantially equal to the length of said pocket thereby to permit said umbrella to be carried in said pocket with the upper end of said umbrella not extending above the wearer's hip whereby the wearer can walk, sit and bend freely without unsightly bulging from or interference with said umbrella in said pocket.
